UNITED STATES PATENT OFFICE

1,929,483

AUTOGRAPHIC REGISTER

Robert J. Copeland, Toronto, Ontario, Canada

Application May 7, 1932. Serial No. 609,952

11 Claims. (Cl. 282—16)

The principal objects of this invention are to greatly enhance the scope of use of the autographic register, providing a device which will permit the use of "the fan-fold" triple sheet of paper, providing two duplicate copies of the original which may be withdrawn from the device attached together or separated or attached to or separated from the original as the user may desire.

10 A further object is to provide a structure which will be very easily manipulated and which provides for the storage of an ample supply of invoice paper and which may also accommodate the record duplicate in a sealed compartment.

15 The principal features of the invention consist in the novel construction and arrangement of parts whereby the continuous "fan-fold" sheet is drawn between parallelly arranged guide members supported from the sides of the register and 20 which may or may not be adapted to sever the folded longitudinal edges of the "fan-fold" sheet, said transverse members being constructed to support carbon sheets between the longitudinally folded members of the "fan-fold" sheet.

25 A further important feature consists in the novel construction and arrangement of the means for gripping and withdrawing the sheets after they have been written upon and also the novel arrangement of the means for severing the sheets 30 withdrawn.

A still further feature of importance consists in the novel arrangement of a closed cabinet at one end of the register into which the office copy of the bill is fed concurrent with the withdrawal of 35 the sheet.

In the accompanying drawings, Figure 1 is a perspective view of my improved form of autographic register.

Figure 2 is a longitudinal mid-sectional view 40 through the structure shown in Figure 1.

Figure 3 is an enlarged cross-sectional view showing a modified form of means for gripping the sheets at the bottom end.

45 Figure 4 is an enlarged perspective detail showing the separating and carbon-holding members arranged at the head end of the register.

Figure 5 is a plan view of each of the three successive separator members for dividing the 50 several sheets.

Figure 6 is a further enlarged sectional view taken transversely of the separating members illustrated in Figures 4 and 5.

55 Figure 7 is a longitudinal sectional view similar to Figure 2, showing the arrangement of a stor-

age receptacle for the carbon copy taken from the bottom of the "fan-fold" sheet.

Figure 8 is a plan and part sectional detail view of the roller mechanism for directing the carbon sheet into the storage receptacle. 60

Figure 9 is a plan view of the box illustrated in Figure 1, showing the cover member thrown back and the sheet-withdrawing member moved to its outward position.

Figure 10 is a plan view of a length of the "fan-fold" sheet used with the present device shown spread flat and illustrating the manner in which the sheets are perforated for separation. 65

Figure 11 is a perspective detail showing a pile 70 of the "fan-fold" sheets as prepared for use in the register.

In the operation of autographic registers it has been proposed to use what is commonly known as a "fan-fold" sheet, that is a sheet 75 which is folded back and forth several times in its width. The use of such a sheet has not been found satisfactory, as there are a number of features which render its use in ordinary office practice uncertain and difficult. 80

The present invention purports to overcome these difficulties and to enable the use of a "fan-fold" in a simple and economical manner.

In the device here shown the casing 1 of the autographic recorder is of a rectangular form, 85 having the side walls 2 sloping upwardly toward the back which has an opening 3 through which the folded paper sheet 4 is inserted.

An opening 5 is arranged in the top of the casing at the back end and across this opening 90 is arranged a roller 6 and a guide bar 7, around which the endless length of folded paper is arranged to pass.

An open frame cover 8 is secured by the hinges 9 to the back end of the casing adjacent to the opening 5 and this frame has a pair of side bars 10 which extend inwardly over the side edges of the record sheet which is drawn over the top plate 11.

A cross bar 12 connects the ends of the side 100 bars 10 and this is preferably in the form of a wire flattened on one side to fit snugly down to the paper sheet and it is formed with an offset central portion 13, the purpose of which will be later explained.

Adjacent to the opening 5 and extending from side to side of the top are a plurality of thin transverse plates. The lower one of these 14, located as illustrated in Figure 4 and shown 110 in plan in the upper portion of Figure 5, is

spaced at one end by a plate 15 from one side of the top plate 11 and the plate 14 extends transversely across the top of the register and is provided with a slot 16 which extends almost the entire length of the plate.

The strip of fan-folded paper which is brought over the roller 6 lies along the top plate 11 with the plate 14 extending into the opening between the lower and second section from one side, that is to say, the two lower sections of the "fan-fold" paper have their open side arranged on the side from which the plate 14 projects, consequently the plate extends in between the sheets and holds a carbon sheet 17 disposed between said sheets by having the end thereof threaded through the slot 16 therein.

The plate 14 is held rigidly in place by a pair of threaded studs 18, projecting upwardly from the one side of the top plate 11.

20 A similar pair of studs 19 are arranged transversely opposite the studs 18 and a spacing plate 20 is placed thereover and a plate 21 similar to the plate 14 is arranged to extend parallelly over the plate 14 and is spaced a short distance 25 thereabove by the plates 22 fastened to the underside thereof at each end.

The plate 21 is provided with a longitudinal slot 23 to receive the edge of a carbon sheet 24.

30 The edge of the plate 21 adjacent to the roller 6 is bevelled at one end, forming a cutting edge 25 which intersects the fold of the top and intermediate sheet of the "fan-fold" paper strip and at the opposite end the plate is cut away at 26 to clear the edge of the paper.

35 A third plate 27 is shown in Figure 5 which is the reverse of the plate 21, having a cutting edge 28 at the opposite end to be used if a four-fold "fan" sheet is desired, or this may be placed at the bottom in place of the plate 14 if it is desired to sever both longitudinal edges of the 40 three-page "fan-fold" sheet.

The edges of these plates extending toward the roller 6 are preferably curved slightly upward, as illustrated in Figure 6 and each of them 45 is preferably formed with a broad V-shaped notch 29, the purpose of which will be further described.

It will be noted on reference to Figures 4 and 50 5 that the plates 14, 21 and 27 are formed of two spaced longitudinal pieces connected together by short strips at the end. These short strips form the necessary spacers to space the longitudinal plates a sufficient distance from each other to permit the free passage of the 55 paper sheet which it is desired to pass therethrough.

These paper sheets are particularly illustrated in Figure 10, which shows a three page sheet on a reduced scale and spread out flat.

60 It will be noted on reference to this drawing that the three longitudinal strips are separated by lines of perforations 30 and 31 and these perforations are preferably alternately long and short, so that as they come in contact with the bevel cutting edges of the spacing plate they will be quite easily severed.

The longitudinal strip is divided transversely to separate the pages by perforated lines 32 and a long perforation or slit 33 is arranged mid-way of the width of each sheet and it is because of this long perforation that the V-notch 29 is formed in the lead-in edges of the spacing plates.

In the travel of the sheet, the edges of the slits 33 are liable to separate and bulge and on coming in contact with the convergent edges of the

V-notch 29 the bulge is smoothed down to pass easily under the plate without catching.

It will be noted that at the point of intersection of the longitudinal perforated lines 30 and 31 with the transverse lines of perforations 32, 80 there are large corner perforations 34. These are formed in a very simple manner in the trimming of the sheets in their folded pad form as illustrated in Figure 11. The longitudinal sheets are folded back and forth along the page perforation 32 and when the pad is of the desired thickness, the corners are trimmed by a rounding tool. This cuts away the paper to form the perforations 34 and when the sheet in its fan-fold shape moves through the machine, each transverse perforation has a V-shaped opening 34' at each side, 90 which ensures the sheet being torn at the proper point for severance.

A pair of channel guides 35 are arranged one at each side of the casing 1 and a plate 36 resting on top of the casing is formed with side flanges to engage these guides and a shelf 37, shown particularly in Figures 2 and 3, of angle formation in cross section is secured to the end of the plate outside of the casing.

100 A rib 38 projects upwardly from the top of the member 37 mid-way between the sides and adjacent to the offset 13 of the cross bar 12 of the hinged top plate 11 and a gripping member 39 is mounted on the member 37 to extend in close 105 to the offset of the cross bar 12 and to grip the paper of the "fan-fold" sheet back of the rib 38.

The gripping member 39 illustrated in Figures 1, 2 and 9, is in the form of a lever which extends through a slot 40 in the member 37 and the lower end 41 thereof forms a hand grip by means of which the sliding plate is drawn out from the casing. A double service is thus performed in the one operation. First, upon grasping the handle it tilts upon its pivot in the slot and grips 115 the paper sheet and it then pulls the sliding plate and the paper outwardly together.

The movement of the sliding plate is limited so that when it is pulled out to its maximum length the cross perforations 32 of the fan-fold sheets are in alignment with the forward edge of the cross bar 12 and the operator with a lifting movement tears the sheet across the perforated line.

120 The slit 33 is provided centrally of the width of the sheet so that the tearing action will jump across the offset portion of the cross bar without being falsely torn.

It may be found desirable instead of forming the slit 33 in one length, it may be divided into 125 two short slits 42 separated by a short central perforated portion as illustrated in Figure 9.

The preferred form of gripping member is shown and described as that illustrated in Figures 1 and 2 but other forms of grips may be provided. An example of another form is shown in Figure 3, in which the grip member 43 is pivoted on a cross pin 44 and is held to grip the paper by means of a spring 45. With this form of grip the outer end is pressed downwardly when the 130 sliding plate is being returned and the tripping end is thus raised to extend over the bottom of the sheet, which projects past the cross bar 12 at the offset portion 13, which allows the gripper to engage the same.

135 The operation of this device is extremely simple. A pad of the "fan-fold" paper such as illustrated in Figure 11, is placed in the casing 1 through the opening 3. The end of the paper is then passed around the guide bar 7 and roller 140

6 with the hinged cover plate thrown back. The folded edges of the sheet are severed for the length of one page simply by tearing or by the use of a paper knife and the first of the cross plates 14 is then laid across the lower sheet, a sheet of carbon paper being first secured therein by having the end inserted through the slot 16. The second sheet of the "fan-fold" strip is then laid over the plate 14 and carbon sheet and the 10 second spacer plate 21 also having a carbon sheet inserted therein is then placed over the second sheet and the last of the cross plates is then placed over the last sheet of the "fan-fold" strip. This last plate 27' is merely a holding plate to 15 hold the upper sheet of the "fan-fold" strip in position.

The "fan-fold" sheet is drawn down over the top plate 11 until the end edge overlaps the gripping rib 33. The cover plate is then swung down and the cross bar holds the sheet in position. The sheet is then ready to be written on and when an order has been completed, the operator grasps the handle 41 of the grip lever 39 and the gripping end engages the sheet over 25 the rib 33. By pulling on the handle the plate 36 is drawn out, pulling with it the pages that have been written upon and as these are pulled out the "fan-fold" sheet is drawn from the pack within the casing and passing over the roller the 30 several portions follow between the spacer plates and where the spacer plates are arranged with the cutting edges to cut the longitudinal perforated edges, the knife blade portions in their bevelled position slit the short lengths of paper 35 between the long perforation quite readily. The carbon sheets which are threaded through the slots in the spacer plates remain in the same position, the sheets sliding freely above and below the same.

40 A construction of autographic register such as described is extremely simple, it is easily operated and practically fool-proof.

It will be seen that the spacer plates may be arranged so that the several strips of the "fan-fold" sheet will be severed longitudinally, or 45 either one or other of the longitudinal folds may be severed as desired.

When the plates are arranged in their relative position to accomplish the desired result for 50 longitudinal slitting, no further change is required, even when resetting to place a new pad and when it is desired to place a new pad it is not necessary to either loosen or remove the spacer plates, as the ends of the "fan-fold" strip 55 may be fed in from the roller side if desired.

In some forms of business it is desirable that the office copy of the orders be retained so that the clerk writing the order may not have access thereto and in order to provide for such use I 55 have devised an additional cabinet receptacle 46 as illustrated in Figures 7 and 8. This may be attached to the casing 1 by being secured with bolts 47 to the discharge end of the casing.

The sloping top 48 of the cabinet 46 is arranged at a lower level than the sloping top of 60 the casing 1 to permit the sliding cross bar 37' to move thereover. The plate 36 in this instance is removed and the side guides and cross bar 37' form an open frame. A slot 49 is provided in 70 the end of the fixed top of the casing 1 to permit the bottom sheet of paper to pass downwardly.

A slot 50 is formed in the top of the cabinet 46 close to the end secured to the casing and a roller 51 mounted in suitable journals extends 75 across this slot.

It is preferred to provide a spur gear 52 at one or both ends of the roller 51, the teeth of which are engaged by a spur pinion 53 mounted on a second roller 54. The surfaces of these rollers engage and the paper sheet of the carbon copy 80 is passed downwardly therebetween.

Upon the ends of the spindle of the roller are rotatably mounted the friction wheels 55 which are engaged by the edges of the side members operating in the guides 35. Ratchet wheels 56 are rigidly mounted on the spindles of the roller 51 and pawls mounted on the friction rollers engage the ratchets to turn the roller in one direction when the sheets are being drawn out, but when the frame carrying the sheets outwardly is being returned, the pawls slip over the ratchet.

With this arrangement of rollers in the storage cabinet the bottom sheet bearing the record copy is fed through the slot 49 and drawn into the cabinet by the operating roller as the frame carrying the first and second copies is moved outwardly, thus when the top sheets have been moved out to a position to be severed from the main strip, the office copy has been simultaneously carried into the closed cabinet.

100 The cabinet is provided with a suitable lock.

The "fan-fold" sheet is admitted to be the positive means of maintaining an exact register, the one form with the other so that carbon copies will be produced with the dates, numbers 105 and other entries in their precise relative positions on the sheets and this device has been produced for the purpose of utilizing this form of sheet to the best advantage.

What I claim as my invention is:

110 1. An autographic register having a writing top, and a plurality of spacing plates spaced above and extending across said top and adapted to extend between the sheets of a fan-folded paper strip, said spacing plates being provided at the 115 end with cutting means for serving the longitudinal fold lines of the strip, and said spacing plates having means for holding a carbon sheet.

2. An autographic register having a writing top, and a plurality of plates spaced one above the 120 other and spaced above said writing top and extending thereacross and adapted to separate the sheets of a fan-folded paper strip, each of said plates having a slot extending thereacross to receive the end of a carbon sheet.

125 3. An autographic register having a writing top, and a plurality of plates spaced one above the other and spaced above said writing top and extending thereacross and adapted to separate the sheets of a fan-folded paper strip, each of said 130 plates having a slot extending thereacross to detachably receive the end of a carbon sheet, said plates having cutting means at the end of the slots thereof for intercepting and severing the longitudinal fold edges of the strip as it passes said 135 carbon-holding plates.

4. In an autographic register, a writing top over which a fan-folded paper strip is adapted to pass, a plurality of interchangeable superposed carbon-holding plates extending transversely of 140 the fan-fold strip between the folded lengths thereof, certain of said plates having sharpened extremities for severing the longitudinal fold lines of the strip, and means for detachably securing said plates in a desired predetermined assembled relation to effect the severing of one or more of the longitudinal fold lines of the fan-fold strip.

145 5. An autographic register having a writing top, a plate rigidly secured at its end and spaced 150

- above and extending across the writing top and adapted to extend between the longitudinal sheets of a fan-folded strip of paper, a plate secured at the end and spaced above the aforesaid 5 plate and extending across the writing top and adapted to extend between another pair of sheets of a fan-folded strip of paper, each of said plates having a longitudinal slot to receive and hold the folded end of a carbon sheet, and means for 10 drawing the fan-folded paper sheets lengthwise, said slotted plates having means at the ends of the slots thereof for severing the longitudinal fold edges of the strip.
6. An autographic register as claimed in claim 15 5 in which the means for severing the longitudinal fold edges comprises bevel cutting surfaces arranged on said transversely arranged plates to sever the longitudinally folded edges of the fan-fold sheet as it is drawn past said spaced trans- 20 verse plates.
7. An autographic register having a writing top, a plurality of spacing plates extending across said writing top at one end and spaced therefrom and spaced from each other and each having a 25 guiding edge to guide a fan-fold paper sheet, said guiding edges having a central V-shaped notch, a transversely perforated fan-fold sheet extending past said guiding member, the transverse perforations having a long slotted portion in the 30 middle of the sheet, means extending across the sheet forming a severing edge and having an offset central portion, and means for gripping the paper sheets at said offset central portion to draw them outward past said guide plates and severing 35 edge means.
8. An autographic register having a writing top with studs arranged adjacent to the sides of the writing top and close to one end, plates extending across the writing top and having spacing members at the ends and having holes through which 40 said studs extend, said plates being mounted in spacing positions to permit the treading there-

between of the sheets of a fan-fold strip of paper, said transverse spaced plates having cutting edges adapted to engage and sever the longitudinal edges of the fan-folded paper strip, carbon sheets secured to said transverse plates, means for drawing the fan-fold paper strips past said transverse plates and carbon sheets in a direct alignment, and means for severing the sheets transversely. 80

9. An autographic register, comprising a writing top, transverse plates spaced apart above the writing top at one end thereof and having cutting edges to sever the longitudinal folds of a fan-fold strip of paper as it is advanced over said top, a 85 slidable member telescopically associated with said writing top and extensible to advance the 90 fan-fold strip, a slotted casing arranged at one end of the writing top below said slidable member to receive the bottom sheet of the fan-fold strip, and means actuated by the sliding extending movement of said slidable member for feeding 95 the bottom sheet into said slotted casing.

10. An autographic register having a writing top, spacing members extending across the writing top having means for severing the longitudinal edges of a fan-fold strip of paper, a casing 100 arranged at one end of the writing top having a slot therein, rollers arranged within said casing below the slot adapted to grip the bottom sheet of paper of the severed fan-fold strip, a sliding member adapted to grip and pull the fan-fold 105 sheets past said spacing and severing means, and means operated by said sliding member for operating said rollers.

11. An autographic register as claimed in claim 10 having friction wheels rotatably mounted on 110 said rollers and engaging said sliding member and rotated thereby, ratchet wheels mounted on said rollers, and ratchet dogs carried by said friction wheels and engaging said ratchet wheels to rotate the rollers. 115
